UNITED STATES PATENT OFFICE.

JAMES L. WALKER, OF GRAND ISLAND, NEBRASKA.

FLYING-MACHINE.

1,111,627.

Specification of Letters Patent. Patented Sept. 22, 1914.

Application filed July 22, 1913. Serial No. 730,491.

To all whom it may concern:

Be it known that I, JAMES L. WALKER, a citizen of the United States, residing at Grand Island, in the county of Hall and 5 State of Nebraska, have invented new and useful Improvements in Flying-Machines, of which the following is a specification.

This invention relates to flying machines of the aeroplane class, and one of its principal objects is to provide a machine which possesses both inherent and automatic stability, and which, under all ordinary conditions, when its balance is disturbed, will 15 of its own volition adjust itself for the action of the air to return it to balanced position.

A further object of the invention is to provide a flying machine which embodies means operative under abnormal conditions 20 to prevent tilting of the machine under excess pressures from above, as well as loss of the fore-and-aft stability when the machine strikes an air hole and plunges downwardly and forwardly, thus preventing it from 25 "turning turtle" in the air.

A still further object of the invention is to provide a flying machine having a main supporting surface of comparatively small area, and a rudderless tail portion having a 30 supporting area greater than that heretofore employed, said tail portion coöperating with the main surface to give the desired lifting action, and also serving, by being made devoid of rudders or vaned surfaces, to skid 35 to a degree when the machine tilts laterally to bank the machine properly for a turning motion or to restore it to a normally balanced position.

A still further object of the invention is 40 to provide a flying machine having a low center of gravity, a novel arrangement of the drive propeller to gain greater power and speed, and a novel construction and arrangement of steering head which is both 45 automatic and manually operative.

The invention consists of the novel features of construction, combination and arrangement of parts hereinafter fully described and claimed, reference being had to 50 the accompanying drawings in which—

Figure 1 is a front elevation of a flying machine embodying my invention. Fig. 2 is a side elevation of the same. Fig. 3 is a top plan view of the machine. Fig. 4 is a 55 vertical longitudinal section thereof. Figs. 5 and 6 are vertical transverse sections on

the lines 5—5 and 6—6 of Fig. 3. Fig. 7 is a bottom plan view of the main plane. Fig. 8 is a diagrammatically perspective view of the steering head and controlling devices associated therewith. Fig. 9 is a detail fore-and-aft section through one of the wings of the main plane.

Referring to the drawings, 1 designates the main frame of the machine, having head 65 and tail frame extensions 2 and 3 and carrying a boat-shaped car 4 which is preferably of tapered or streamline form, suitable cushioned launching and landing wheels 5 being provided when desired. The sides of the 70 main frame are preferably provided with coverings 6 of fabric or other suitable material, to give increased lateral stability and inclose the parts of the frame-work to diminish head resistance, the machine being otherwise wholly devoid of vertical surfaces of 75 any extent on which the air may have acting influence. The main frame carries a supporting plane or surface 7, which is curved transversely, or in a fore-and-aft direction, 80 to present a desired lifting angle of incidence when the machine is in flight. This plane or supporting surface is preferably formed, as usual, of longitudinal spars or 85 stringers 8, ribs 9, and a suitable fabric covering 10. The plane which has approximately $\frac{1}{3}$ the normal lifting capacity of a conventional plane for a machine of the same or any given size and weight, is double-surfaced and imperforate in rear of the camber point and provided with openings or air 90 gaps 9^a in advance of the camber point. Beneath the front portion of each wing of the plane is a stabilizing flap or auxiliary plane 11, coextensive in length and width with 95 apertured portion of said wing and hinged or pivoted at its forward edge, as at 12, to the leading edge of the wing, so as to tilt or swing vertically on a horizontal transverse axis. The flap 11 is constructed preferably 100 in a similar manner to the main plane and is provided at its rear edge with a stiffening or reinforcing strand 13. To this strand are attached the forward ends of cords or wires 14 which are connected at their rear 105 ends by coiled contractile springs 15 to the rear edge of the main plane. Resilient flexible connections are thus provided which are normally taut, the flap 11 being held against the supporting plane so as to close the open- 110 ings 9^a by the pressure of the wind when the machine is in flight and having the same

angle of incidence as the forward portion of the plane, the flap normally or under such conditions, forming a part of said supporting plane. The springs 15 are, accordingly, 5 normally held expanded or under tension, their tendency to contract and swing the flap downward being overcome by the air pressure resistance from below. When, however, the front part of the plane 7 is 10 struck by sudden or excess bodies of air tending to force the head of the machine downward and to destroy longitudinal stability, the flap 11 is depressed or opened, allowing the greater portion of the excess 15 pressure to pass off while the flap takes an increased angle of incidence and prevents tilting of the machine. As soon as such excess pressure from above is removed the flap returns to normal position. If the machine 20 suddenly dives downwardly and forwardly as when striking an air hole the pressure from below upon the flap is relieved and the springs draw the flap downwardly to an increased angle of incidence, providing a 25 forward supporting surface which checks the speed of descent and the further tilting of the machine on its transverse axis, and prevents the machine from "turning turtle" or turning over in the air, allowing the aviator to regain control.

The tail frame extension 3 carries a tapering tail plane 16, set at a sustaining angle of incidence, and having an area equal to about one-half the area of the main plane 35 and designed to support approximately $\frac{1}{2}$ as much in proportion to its area as the plane 7, or about $\frac{1}{3}$ of the total weight of the machine in flight, thus compensating for the sustaining deficiency of the plane 7, 40 and coacting therewith to provide an adequate sustaining surface. For instance, in a machine weighing 1000 lbs., and having a plane 7 of 200 sq. ft., and a lifting capacity of 800 lbs., the tail may have an area of 100 45 sq. ft., and a lifting capacity of 200 lbs. By thus proportioning and distributing the sustaining ratios of the main plane and tail, greater longitudinal stability and a higher degree of "assiette" or aerial floating efficiency of the supporting surface are secured. By this construction the machine 50 is also rendered auto-balancing laterally. For example, as it tips to the right the tail, having weight but no rudder or other vertical surface, will skid to the right, thereby turning the machine to the left and causing an upward pressure on the right wing, by which the balance is restored. Similarly, as 55 the machine tips to the left, the tail will skid in such direction, causing an additional lifting pressure on the left wing, whereby the balance is restored.

The motor 17 is arranged upon the car or low down upon the main frame in line with 60 the center of gravity and pressure, while the

driving propeller 18 is arranged above the trail portion of the tail frame, at a point where it acts upon undisturbed air, whereby its driving efficiency is increased. The thrust of the propeller is transmitted on a 70 line parallel with the line of flight through the mounting of the propeller upon a longitudinally extending shaft 19 suitably driven from the motor, and which extends in a plane coincident with a line intersecting the 75 axes of the machine, allowing all of the compulsive force of the propeller to be utilized with a reduction of slippage. Furthermore, the propeller is thus so positioned that the currents of air therefrom are dissipated at a point where their action upon surfaces tending to destroy the normal balance of the machine is overcome.

The head frame extension 2 carries a steering head, which operates to normally 85 prevent skidding, and to automatically maintain lateral and longitudinal stability, and which is manually adjustable for stabilizing and steering actions. This steering head comprises a compound X-shaped 90 rudder consisting of two crossing planes 20 and 21 arranged at right angles to each other and in opposite oblique lines to the direction of flight. This compound rudder is mounted to tilt vertically and laterally 95 upon a universal or gimbal joint 22. Mounted on the head frame extensions between said rudder and the supporting surface is a horizontal transverse shaft 23, extending to equal degrees on opposite sides of the 100 longitudinal axis of the machine and carrying inner small stabilizing planes 24 and 25. Fixed to said shaft 23 to rock therewith in a fore-and-aft direction is a staff 26. Journaled on the upper arm of said staff are 105 pulleys 27, and 28, and journaled on the lower arm of said staff are pulleys 29 and 30, while upon an intermediate portion of the staff are journaled pulleys 31, 32, 33 and 34.

Arranged upon the machine in proximity to the aviator's seat 35 is a controlling device comprising an X-shaped compound lever, formed of the pair of levers 36 and 37 having the same angular arrangement as 115 the rudder planes 20 and 21, said controlling device being universally movable upon a gimbal joint 38. The upper arm of each lever 36 and 37 is provided with a handle or hand-grip 39, while the lower arm of each of said levers is provided with a foot-loop 40, whereby the lever may be adjusted by hand or foot power, or both, at will. A cord or cable 41 leads from the upper right hand arm of the lever 36 over the pulley 34 and upwardly and forwardly over the pulley 28 and is connected with the upper rear corner of the rudder plane 21, while a cord or cable 42 leads from the upper left hand arm of the lever 37 upwardly beneath 120 125 130

the pulley 31 and upwardly and forwardly over the pulley 27 to the upper left hand corner of the rudder plane 20. A third cord or cable 43 leads from the lower right hand 5 arm of the lever 37 over the pulley 33 and downwardly and forwardly over the pulley 30 and is adapted to the rear right hand corner of the rudder plane 20 while a fourth cord or cable 44 leads from the lower left 10 hand arm of the lever 36 to and downwardly over the pulley 32 and thence over the pulley 29 to the lower rear left hand corner of the rudder plane 21. It will thus be understood that when the compound 15 controlling lever is rocked in a fore-and-aft direction on the joint 38, motion may be transmitted to the compound rudder to tilt the same upwardly and downwardly to steer the machine in a vertical plane, while 20 by giving a lateral turning motion to the controlling device similar to that in adjusting the steering handle of a bicycle or like vehicle, the compound rudder may be adjusted laterally in either direction to steer 25 the machine to the right or left. Any of these movements may also be obtained and employed to steer and balance the machine at the same time, as will be readily understood.

30 When the machine is in flight and a disturbing pressure comes from below and tilts the planes 24 and 25 upwardly, motion is communicated to the compound rudder to adjust the same to a compensating degree, to 35 prevent upward tilting motion of the aeroplane, while when excess pressure comes from above and tilts the planes 24 and 25 downwardly, the compound rudder is adjusted in the opposite direction to prevent 40 the aeroplane from tilting downwardly and forwardly, whereby the longitudinal stability of the machine is automatically preserved during all ordinary conditions of flight.

45 From the foregoing description, taken in connection with the drawings, the construction and mode of operation of my improved flying machine will be readily understood, and it will be seen that a machine is provided which effectually attains the objects sought and which simulates to a high degree the balancing actions of a bird in flight, with resultant advantages in relieving the aviator of anxiety and strain in controlling the machine.

Having thus described my invention, I claim:

1. A flying machine comprising a body, head and tail frames projecting therefrom, 60 steering and balancing mechanism mounted solely upon the head frame, the tail frame being devoid of vertical surfaces, a supporting surface carried by the main frame and of insufficient area and lifting capacity to 65 sustain the machine in flight, a horizontal

tail plane mounted upon the tail frame of less area and lifting capacity than the main plane, but of sufficient area and lifting capacity for coöperation with the main plane to sustain the machine in flight, a motor 70 mounted upon the main frame below the supporting surface, a propeller arranged above the tail plane for rotation on a downwardly and forwardly inclined axis, said propeller receiving motion from said motor. 75

2. A flying machine comprising a main frame, head and tail frames carried by the main frame, the head frame being arranged above the horizontal level of the tail frame and the latter being wholly devoid of vertical surfaces, steering and balancing mechanism mounted wholly upon the head frame, a main supporting plane, mounted upon the main frame, said supporting plane being of an area and lifting capacity insufficient 80 to sustain the machine in flight, a horizontal tail plane mounted on the tail frame and of less area and lifting capacity than the main plane, but of sufficient area and lifting capacity for coöperation with the main 85 plane to sustain the machine in flight, a motor mounted upon the main frame below the supporting surfaces, a propeller mounted above the tail plane, and a shaft carrying said propeller and inclining downwardly and forwardly therefrom, said shaft being driven from said motor. 90

3. A flying machine comprising a main frame, including a pendant body shaped car, head and tail frames projecting from the main frame, the head frame being arranged at a higher horizontal level than the tail frame, steering and balancing mechanism mounted solely upon the head frame, the tail frame being devoid of vertical surfaces, 100 a main supporting plane mounted upon the main frame above the car, said plane being of an area and lifting capacity insufficient to sustain the weight of the machine in flight, a horizontal tail plane mounted upon 105 the tail frame, said tail frame being of less area and lifting capacity than the main plane but of sufficient area and lifting capacity for coöperation with the main plane to sustain the weight of the machine in 110 flight, a motor within the car below the main supporting surface, a propeller mounted above the tail plane, and a shaft carrying said propeller and operated from the motor, said shaft extending at a downward and 115 forward angle of inclination from the propeller to the motor.

4. A flying machine comprising a main frame including a body shaped car, head and tail frames projecting from the main 125 frame, the head being arranged at a higher horizontal level than the tail frame, and the latter being wholly devoid of vertical surfaces, a main supporting plane carried by the main frame above the car, said main 130

frame being of insufficient area and lifting capacity to sustain the weight of the machine in flight, vertical surfaces between said plane and the sides of the car, a horizontal tail plane mounted upon the tail frame and of less area and lifting capacity than the main plane but of sufficient area and lifting capacity for coöperation with the main plane to sustain the machine in flight, a motor mounted within the car below the main plane, a propeller upon the tail frame above the tail plane, and a shaft carrying said propeller and driven from the motor said shaft extending on a downwardly and forwardly inclined plane from the propeller to the motor.

5. A flying machine including a main plane, a flap pivoted beneath the forward portion of said plane to fold against the same under air pressure, and resilient flexible connections between the flap and rear portion of the main plane tending to move said flap downwardly and operating to adjust it downwardly to an increased angle of incidence when the air pressure on said flap is reduced to a determined extent.

6. A flying machine including a curved main plane, double-surfaced in rear of its camber point and perforate in advance of such point, a flap pivotally mounted beneath the perforate portion of the main plane and adapted to fold upwardly against the same under air pressure, and resilient connections between said flap and the rear portion of the main plane tending to draw said flap downwardly, and acting to move the flap to an increased angle of incidence when the air pressure thereon is decreased to a determined extent.

40. 7. A flying machine including a gliding

structure, a universally movable steering head comprising a pair of planes crossed X fashion obliquely to the line of flight, a controlling device comprising a universally mounted X-shaped lever, and connections 45 between the arms of said controlling device and the wings of the steering planes for adjusting said steering head vertically and laterally.

8. A flying machine including a gliding 50 structure, a steering head universally mounted thereon and comprising a pair of planes crossed in X formation obliquely to the line of flight, a horizontal transverse rock shaft, a vertical staff carried by said 55 shaft, pressure planes mounted upon the shaft on opposite sides of the longitudinal center of the machine, a controlling device comprising a universally mounted X-shaped lever, and flexible connections between the 60 arms of said lever and the wings of the planes of the steering head, said connections having a running and guided engagement with the said staff.

9. A flying machine having a supporting 65 surface comprising a plane perforate in advance of its camber point, a flap normally arranged to close said perforate portion of the plane, said flap being movable downwardly under excess air pressure to uncover 70 said perforate portion and form a vent, and means for yieldingly opposing a resistance to the downward movement of the flap.

In testimony whereof I affix my signature in presence of two witnesses.

JAMES L. WALKER.
